DOLL WITH LOLLIPOP EYES

Robert H. Ross and Claire C. Ross,
North Hollywood, Calif.

Application April 26, 1954, Serial No. 30,192

Term of patent 14 years

(Cl. D34—4)

Fig. 1.

Fig. 2.

Fig. 3.

Fig. 1 is a front elevational view of a doll with lollipop eyes, showing our new design;

Fig. 2 is a side elevational view thereof, on a reduced scale; and

Fig. 3 is a rear elevational view thereof.

We claim:

The ornamental design for a doll with lollipop eyes, as shown.

Reference is had to the file of this patent.
